(57) **CLAIM**

The ornamental design for a headset, as shown and described.

DESCRIPTION

FIG. 1 is a front view of a headset (e.g., an audio headset, a neurostimulator charging headset, a neurostimulator interfacing headset, or any combination thereof), showing our new design;

FIG. 2 is a rear view thereof;

FIG. 3 is a left side view thereof;

FIG. 4 is a right side view thereof;

FIG. 5 is a top view thereof;

FIG. 6 is a bottom view thereof;

FIG. 7 is a top-front-left perspective view thereof;

FIG. 8 is a top-front-right perspective view thereof;

FIG. 9 is a top-rear-left perspective view thereof;

FIG. 10 is a top-rear-right perspective view thereof;

FIG. 11 is a bottom-front-left perspective view thereof;

FIG. 12 is a bottom-front-right perspective view thereof;

FIG. 13 is a bottom-rear-right perspective view thereof; and,

FIG. 14 is a bottom-rear-left perspective view thereof.

The shade lines show surface contour.

The broken line showings of cable ends are environmental, and the broken lines form no part of the claimed design.

1 Claim, 14 Drawing Sheets
